Filed Sept. 13, 1966, Ser. No. 3,837

Term of patent 14 years

(Cl. D24—1)

FIG. 1

FIG. 2

FIG.3

FIG.4

FIG.6

FIG.5

FIG. 1 is a perspective view of a dental jet cleansing unit or the like, embodying our new design;

FIG. 2 is a front elevation thereof;

FIG. 3 is a rear elevation thereof;

FIG. 4 is a left side elevation thereof;

FIG. 5 is a right side elevation thereof; and

FIG. 6 is a top plan view thereof.

The hose member is broken away to indicate indeterminate length. The broken line showing of the hose and nozzle adapter has been omitted in FIGS. 2-6 inclusive for ease of illustration.

The dominant features of our design reside in those portions shown in full lines in the drawings.

We claim:

The ornamental design for a dental jet cleansing unit or the like, as shown and described.
